PAUL H. GEIGER, OF ANN ARBOR, MICHIGAN, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed June 20, 1928, Serial No. 286,901. Renewed February 7, 1930.

My invention relates to railway traffic controlling apparatus and particularly to apparatus of the type comprising governing means controlled by energy received from the trackway.

I will describe two forms of railway traffic controlling apparatus embodying my invention and will then point out the novel features thereof in claims.

10 In the accompanying drawings, Fig. 1 is a diagrammatic view showing one form of railway traffic controlling apparatus embodying my invention. Fig. 2 is a view showing a modified form of a portion of the apparatus illustrated in Fig. 1 and also embodying my invention.

Similar reference characters refer to similar parts in both views.

Referring first to Fig. 1, the reference characters 1 and 1^a designate the rails of a stretch of railway track over which traffic normally moves in the direction indicated by the arrow. These rails are divided, by means of insulated joints 2, into a plurality of successive track sections only one of which, A—B, is shown complete in the drawing. Train controlling current is supplied to the rails of this section from a suitable source of energy such as an alternator G. The current supplied to the trackway by this alternator may be of a frequency of the order of the usual commercial alternating current such, for example, as 60 cycles or 100 cycles per second.

The supply of current to the track rails is controlled by a coding device designated in general by the reference character X and comprising a plurality of rotatable cams each designated by the reference character C with a suitable distinguishing exponent. The cams 40 C are driven at a constant speed by a suitable motor U which is supplied with current from the alternator G. The cam C¹ is provided with a plurality of swells 8 spaced about its periphery and which swells successively 45 engage a contact 3 to periodically close the contact as the cam C¹ is rotated. In similar manner the cams C² and C³ are provided with different numbers of swells 8 which control contacts 4 and 5, respectively. One terminal 50 of the alternator G is constantly connected with

rail 1 of section A—B, and the other terminal of the alternator is connected with the rail 1^a through one of the contacts 3, 4, or 5 depending upon traffic conditions.

It is manifest that the alternating current supplied to the rails of the trackway by the alternator G is periodically varied at the frequency of operation of the contact of the device X that is interposed between the alternator and the track rail 1^a. The coding device X may be constructed to cause such variations at any reasonable frequencies, but for purposes of illustration, I will assume that the cams C rotate at 20 revolutions per minute, that cam C¹ has 4 swells, that cam C² has 6 swells, and the cam C³ has 9 swells. The selection between the several contacts of the coding device X in accordance with traffic conditions may be accomplished in any suitable manner such, for example, as by means of a home relay H and a distant relay E. The circuits for controlling these two relays from no part of my present invention and are omitted from the drawing for the sake of simplicity. For present purposes it is sufficient to state that home relay H is normally energized but is de-energized when a train occupies the section immediately to the right of point B. The distant relay E is also normally energized but is de-energized when a train occupies either the first or the second section immediately to the right of point B. With the apparatus as thus far described, when relays E and H are both energized so that front contact 6—6^a of relay H and front contact 7—7^a of relay E are closed, current from alternator G, which current I will assume to be of 100 cycles per second, is supplied to the track rails over contact 5 operated by cam C³. Under these conditions the alternating current supplied to the trackway is periodically varied at a frequency of 180 cycles per minute. Current supplied to the trackway under these conditions I will hereinafter term the "proceed code". When relay H is energized and relay E is de-energized, the closing of back contact 7—7^b of relay E includes contact 4 controlled by cam C² in the trackway circuit, and under these conditions the trackway is supplied with 100 cycle current inter-

55

80

85

90

95

100

rupted at a frequency of 120 cycles per minute; this circuit I shall hereinafter term the "caution code". In similar manner when relay H is de-energized, the closing of back contact 6-6^b of this relay completes a circuit from alternator G to the track rails through contact 3 operated by cam C¹. Under these conditions the trackway is supplied with 100 cycle current interrupted at a frequency of 80 cycles per minute, which I will call the "slow code".

A train, indicated diagrammatically at V, is provided with a receiver designated in general by the reference character Q. This receiver comprises two magnetizable cores 11 and 11^a, carried on the train in advance of the forward axle 10, and located in inductive relation with the two track rails 1 and 1^a, respectively. Core 11 is provided with a winding 12 and core 11^a is provided with a winding 12^a, the two windings being connected in series in such manner that the electromotive forces induced therein by train controlling current flowing in opposite directions in the track rails at any instant are additive. The windings 12 and 12^a are connected in series with condenser 32 and the primary 33 of a transformer N, to form a circuit S, which I will term the "pick-up" circuit, and which is tuned to resonance at the frequency of the alternating current in the trackway. The periodically varying 100 cycle electromotive force which is induced in secondary 30 of transformer N by the current in the pick-up circuit is used to control a relay R, through the medium of a relay device which in the form here shown comprises a grid glow tube W. The tube W consists of a grid 35 and two spaced electrodes 34 and 36 enclosed in a sealed envelope filled with a suitable medium such as neon gas. If an alternating electromotive force having a magnitude sufficiently great is impressed across electrodes 34 and 36, of a tube of the type described, the medium surrounding the electrodes becomes conducting and a uni-directional current flows from electrode 34 to electrode 36. The critical magnitude of the electromotive force necessary to cause tube W to become conducting, however, is dependent upon the potential and relative polarity of grid 35 with respect to electrode 34, this critical magnitude decreasing as the potential of grid 35 increases when the grid is positive with respect to electrode 34, but increasing as the potential of grid 35 increases when the grid is negative with respect to electrode 34. Grid potential is supplied to tube W by the secondary 28 of a transformer M, the primary 29 of which is constantly supplied with alternating current from an alternator L at a frequency which is preferably widely different from the frequency of the current in the trackway. The grid circuit for tube W also includes a resistance 31 and the secondary 30 of transformer

N. Secondary 27 of transformer M is connected across the electrodes 34 and 36 of tube W in series with relay R. When no electromotive force is induced in secondary 30 of transformer N, as when no train controlling current is being supplied to the track rails, the total electromotive force impressed on grid 35 of tube W is equal to the electromotive force impressed on the grid by secondary 28 of transformer M. The parts are so proportioned, that under these conditions, tube W remains non-conducting and no current flows in the circuit including relay R. Relay R is therefore de-energized and back contact 15-15^a of the relay is closed. When train controlling current is being supplied to the track rails, however, the 100 cycle electromotive force induced in secondary 30 of transformer N is added to the electromotive force induced in secondary 28 of transformer M, and there are times during each cycle of the electromotive force delivered by alternator L in which the potential of grid 35 reaches a value which renders tube W conducting. Under these conditions a pulsating direct current is supplied to relay R, which current picks-up the relay, so that contact 15-15^b is closed, and the relay stays picked up as long as an electromotive force is induced in secondary 30 by trackway current. As was previously explained, however, the 100 cycle current supplied to the trackway is periodically varied at different frequencies, and it follows that the electromotive force induced in secondary 30 of transformer N is also periodically varied, the frequency of variation being the same as the frequency of variation of the current supplied to the rails. As a result, tube W becomes conducting at the frequency of the current in the track rails, and relay R is operated at this frequency to alternately close its front and back contacts 15-15^b and 15-15^a.

The operation of relay R may be improved in some instances by connecting across its terminals an asymmetrical conductor P. The conductor P shunts the relay during the decrease of current through tube W, and in this manner smooths out the pulsations in the direct current which is supplied to the relay when tube W is conducting.

Associated with relay R is a transformer T comprising a primary 16 and a secondary 17. Direct current is supplied to the primary 16 of transformer T from a suitable source such as a battery D, and the supply of such current is periodically varied in accordance with the frequency at which relay R operates. As shown in the drawing, when relay R is de-energized to close contact 15-15^a, current flows from battery D through the lower half of primary 16 in one direction, but when contact 15-15^b is closed current flows from battery D, through the upper half of primary 16 in the opposite direction. It follows that

when relay R is operated intermittently, the current in primary 16 of transformer T is periodically reversed and reestablished in the original direction at the same frequency as the periodic variations in the trackway current.

As a result of this periodic current in the primary of transformer T there is induced in the secondary 17 an alternating electromotive force of a corresponding frequency, which electromotive force is applied to a plurality of circuits each designated by the reference character F with a distinguishing exponent, and each comprising a reactor 18 and a condenser 19 by means of which the several circuits are tuned respectively to the frequencies of the variations in the train controlling current. For example, circuit F³ is tuned to resonance at the frequency of the interruptions in the proceed code or 180 cycles per minute. A relay K³ is connected across a portion of reactor 18 of circuit F³ through a rectifier J³. In similar manner, circuit F² is tuned to resonance at 120 cycles per minute and a relay K² is connected across a portion of reactor 18 of this circuit through a rectifier J². Relay K¹ is connected, through rectifier J¹ with a portion of reactor 18 of circuit F¹, which circuit is resonant at 80 cycles per minute.

In explaining the operation of the apparatus as a whole, I will first assume that the proceed code is being supplied to the trackway so that the trackway current is being interrupted at a frequency of 180 cycles per minute. Relay R therefore operates at a rate of 180 cycles per minute and alternating current of a corresponding frequency is supplied to each of the circuits F. At this frequency circuits F¹ and F² are detuned so that the electromotive forces across those portions of reactors 18 of these circuits to which the corresponding relays K are connected are comparatively small. Circuit F³ is tuned to resonance at this frequency and the resonant rise of electromotive force in reactor 18 is comparatively large. A comparatively large electromotive force is therefore applied to rectifier J³, resulting in a comparatively large current in the relay K³. When the train is receiving the proceed code, therefore, relay K³ is energized but relays K¹ and K² are de-energized. Under these conditions, current from battery D flows through front contact 24-24^a of relay K³ to light lamp 20, thereby displaying a proceed indication.

I will now assume that the caution code is being supplied to the trackway so that relay R is operating at a frequency of 120 cycles per second. Alternating current of a corresponding frequency is therefore supplied to the circuits F by secondary 17 of transformer T. Under these conditions the current supplied to relays K³ and K¹ is not sufficient to energize the relays, but sufficient cur-

rent is supplied to relay K² to energize this relay. Under these conditions current from battery D flows over back contact 24-24^b of relay K³ and front contact 25-25^a of relay K² to lamp 21, thereby lighting this lamp to indicate caution.

In similar manner when the slow code is being supplied to the trackway, relays K³ and K² are both de-energized but circuit F¹ is tuned to resonance at the frequency of the current now supplied by secondary 17 of transformer T so that relay K¹ is energized and current from battery D flows over back contact 24-24^b of relay K³, back contact 25-25^b of relay K² and front contact 26-26^a of relay K¹ to lamp 22. Lamp 22 is therefore lighted to indicate slow.

If section A-B were occupied by a second train located between train V and point B, train controlling current would be shunted away from train V by the wheels and axles of such second train. As a result relay R would be continuously de-energized. If, for this reason, or for any other reason, relay R should fail to operate intermittently, the supply of energy to all the relays K would be discontinued and these relays would be open. Current would then flow from battery D, over back contact 24-24^b or relay K³, back contact 25-25^b of relay K², and back contact 26-26^b of relay K¹ to lamp 23, thereby lighting this lamp to display a stop indication.

For purposes of explanation, I have described relays K as controlling only the lamps 20, 21, 22, and 23, but it should be understood that these relays may control other train governing means of any suitable type not shown in the drawing.

I have described apparatus which supplies only three codes to the trackway and have shown train carried governing means adapted to distinguish only between these three codes. It should be understood, however, that my invention is not limited to this number of codes but that the equipment could be expanded to provide additional code frequencies and additional tuned circuits on the train to select between such frequencies.

Referring now to Fig. 2, I have shown two grid glow tubes W and W¹, the tubes being arranged to supply relay R with a uni-directional current from secondary 27 of transformer M during both halves of each cycle when the tubes are conducting. To accomplish this result, the terminals of secondary 27 of transformer M are connected respectively with the electrodes 34 of tubes W and W¹, and in similar manner the terminals of secondary 28 of transformer M are connected with the grids 35 of these tubes. The electrical midtaps of secondaries 27 and 28 are connected with secondary 30 of transformer N through a resistance 31 and a double wave rectifier O. One terminal of relay R is connected with the midtap of secondary 27 and

the other terminal of relay R is connected with the electrodes 36 of both tubes, rectifier P being connected across the terminals of the relay to smooth out the pulsations in the current when the tubes are conducting. With the apparatus constructed in this manner, the total electromotive force impressed on the grid of either tube at any instant is equal to the sum or difference, as the case may be, of the electromotive forces induced in the corresponding halves of each secondary of transformer M plus the uni-directional electromotive force supplied by secondary 30 of transformer N through rectifier O. When no electromotive force is induced in secondary 30, as when no train controlling current is being supplied to the trackway, the total electromotive force impressed on the grids of tubes 20 W and W¹ by secondaries 27 and 28 is such that the tubes remain non-conducting and relay R is de-energized to close contact 15—15^a. When an electromotive force is induced in secondary 30, however, as when 25 100-cycle train controlling current is being supplied to the track rails, the grid potentials of the tubes are brought to values which render the tubes conducting, and relay R is supplied with a uni-directional current from 30 secondary 27 of transformer M during both halves of each cycle. This current picks up relay R to close contact 15—15^b, and the relay stays picked up as long as the tubes remain conducting. Due to the periodic variations 35 in the trackway current, it is apparent that the electromotive force induced in secondary 30 is also periodically varied, and it follows that the tubes W¹ and W² are periodically rendered conducting and non-conducting 40 at the frequency of variation of the current in the trackway. Relay R therefore operates at the frequency of variation of the train controlling current to alternately close its front and back contacts 15—15^b and 45 15—15^a, and the remainder of the associated apparatus functions as previously described in connection with Fig. 1.

Although I have herein shown and described only two forms of railway traffic controlling apparatus embodying my invention it is understood that various changes and modifications may be made therein within the scope of the appended claims without departing from the spirit and scope of my invention.

Having thus described my invention, what I claim is:

1. Railway traffic controlling apparatus comprising a stretch of railway track, means for at times supplying the rails of said stretch with train controlling current, a train carried tube comprising two spaced electrodes and a grid in a medium which forms a conducting path between said electrodes when and only when the potential between the electrodes

exceeds a value which depends on the relative potential of the grid with respect to one of said electrodes, a source of alternating electromotive force on the train, a relay, means including said relay for connecting said source across said electrodes, means for varying the relative potential of said grid with respect to said one electrode in accordance with the train controlling current supplied to said rails, and traffic governing means controlled by said relay. 75

2. Railway traffic controlling apparatus comprising means for supplying alternating current to the trackway, means for periodically varying said supply at different frequencies, 80 a train carried tube comprising a first and second spaced electrodes and a grid in a medium which forms a conducting path between said electrodes when and only when the potential between the electrodes exceeds a value which depends on the relative potential of said grid with respect to said first electrode, a relay, a source of alternating electromotive force connected across said electrodes in series with said relay, means connected with the grid of said tube and receiving energy from the trackway for varying the potential of said grid with respect to said one electrode at the frequency of variation of the current supplied to the rails, and traffic governing means controlled by said relay. 85

3. Railway traffic controlling apparatus comprising means for supplying alternating current to the trackway, means for periodically varying said supply, a train carried tube comprising a first and second spaced electrodes and a grid in a medium which forms a conducting path between the electrodes when and only when the potential between the electrodes exceeds a value which depends upon the relative potential of the grid with respect to said first electrode, a first transformer having a primary constantly supplied with alternating current and two secondaries, a relay, means including said relay for connecting one 100 of said secondaries across said electrodes, a second transformer having its secondary connected in series with the other secondary of said first transformer between said grid and said first electrode and its primary receiving energy from the trackway at the frequency of variation of said supply, and traffic governing means controlled by said relay. 105

4. Railway traffic controlling apparatus comprising a stretch of railway track, means for at times supplying the rails of said stretch with periodically varying alternating current, a train-carried tube comprising a first and second spaced electrodes and a grid in a medium which forms a conducting path between said electrodes when and only when the potential between the electrodes exceeds a value which depends on the relative potential of the grid with respect to the first electrode, means controlled by energy received from the track- 115 120 125 130

way for varying the potential of said grid with respect to said one electrode at a frequency which depends upon the frequency of variation of the current supplied to the rails; a relay, a train-carried source of alternating current connected across said electrodes in series with said relay, and traffic governing means controlled by said relay.

5. Railway traffic controlling apparatus comprising a stretch of railway track, means for supplying the rails of said stretch with periodically varying alternating current, a train-carried tube comprising two spaced electrodes and a grid in a medium which forms a conducting path between the electrodes when and only when the potential between the electrodes exceeds a value which depends on the relative potential of the grid with respect to one of said electrodes, a first source of alternating electromotive force on the train, a relay, means including said relay for connecting said source across said electrodes, a second source of electromotive force on the train, a transformer having its primary supplied with energy from the trackway at the frequency of variation of the current in the track rails and having its secondary connected in series with said second train-carried source across said grid and said one electrode, and traffic governing means controlled by said relay.

6. Railway traffic controlling apparatus comprising a stretch of railway track, means for at times supplying the rails of said stretch with alternating current which is periodically varied at different frequencies, a train-carried tube comprising two spaced electrodes and a grid in a medium which forms a conducting path between the electrodes when and only when the potential impressed across said electrodes exceeds a value which depends upon the potential of said grid with respect to one of said electrodes, a train-carried source of electromotive force connected across said electrodes, means located on the train and receiving energy from the track rails for impressing across said grid and said one electrode an electromotive force which renders said tube conducting at the frequency of variation of the current in the track rails, and train-carried governing means selectively responsive to the frequency at which said tube becomes conducting.

7. Railway traffic controlling apparatus comprising a stretch of railway track, means for at times supplying the rails of said stretch with train controlling current which is periodically varied at different frequencies, a train-carried tube comprising two spaced electrodes and a grid in a medium which forms a conducting path between the electrodes when and only when the potential across the electrodes exceeds a value which depends on the relative potential of said grid with respect to one of said electrodes, means for impressing across said electrodes an

alternating electromotive force, means for impressing an electromotive force across said grid and said one electrode, means for periodically varying the electromotive force impressed across said grid and said one electrode in accordance with the variation in the current in the track rails, and traffic governing means controlled by said tube and selectively responsive to the frequency of variation of the current in the current between such electrodes.

8. In combination, a stretch of railway track, means for at times supplying the rails of said stretch with train controlling current which is periodically varied at different frequencies, a train-carried grid glow tube comprising two spaced electrodes and a grid in a medium which forms a conducting path between the electrodes when and only when the potential across the electrodes exceeds a value which depends on the relative potential of said grid with respect to one of said electrodes, a resistance, means connected with said grid and including said resistance for varying the relative potential of said grid with respect to said one electrode at the frequency of variation of the train controlling current, a source of alternating electromotive force on the train, a relay, means including said relay for connecting said source across said electrodes, and traffic governing means controlled by said relay.

9. Railway traffic controlling apparatus comprising a stretch of railway track, means for at times supplying the rails of said stretch with current, a tube comprising two spaced electrodes and a grid in a medium which forms a conducting path between said electrodes when and only when the potential between the electrodes exceeds a value which depends upon the relative potential of the grid with respect to one of said electrodes, a source of alternating electromotive force, a relay, means including said relay for connecting said source across said electrodes, means for varying the relative potential of said grid with respect to said one electrode in accordance with the current in the track rails, and governing means controlled by said relay.

10. Railway traffic controlling apparatus comprising a source of current which is periodically varied, a tube comprising two spaced electrodes and a grid in a medium which forms a conducting path between said electrodes when and only when the potential between the electrodes exceeds a value which depends upon the relative potential of the grid with respect to one of said electrodes, a source of alternating electromotive force, a relay, means including said relay for connecting said source across said electrodes, means for varying the relative potential of said grid with respect to said one electrode at the frequency of variations of current

from said source of current, and governing means selectively responsive to the frequency of operation of said relay.

11. Railway traffic controlling apparatus comprising means for supplying the track rails with alternating current which is periodically varied at different frequencies, a tube comprising two spaced electrodes and a grid in a medium which forms a conducting path between said electrodes when and only when the potential between the electrodes exceeds a value which depends upon the relative potential of the grid with respect to one of said electrodes, a source of electromotive force, a relay, means including said relay for connecting said source across said electrodes, means connected with the grid of said tube and receiving energy from the trackway for varying the potential of said grid with respect to said one electrode at the frequency of variation of the current supplied to the rails, and traffic governing means selectively responsive to the frequency of operation of said relay.

12. Railway traffic controlling apparatus comprising means for supplying the track rails with alternating current which is periodically varied at different frequencies, a tube comprising two spaced electrodes and a grid in a medium which forms a conducting path between said electrodes when and only when the potential between the electrodes exceeds a value which depends upon the relative potential of the grid with respect to one of said electrodes, a source of electromotive force connected across said electrodes, means receiving energy from the track rails for impressing across said grid and said one electrode an electromotive force which renders said tube conducting at the frequency of variation of the current in the track rails, and governing means selectively responsive to the frequency at which said tube becomes conducting.

13. In combination, a train-carried tube comprising two spaced electrodes and a grid in a medium which forms a conducting path between said electrodes when and only when the potential between said electrodes exceeds a value which depends on the relative potential of said grid with respect to one of said electrodes, a source of electromotive force on the train, a relay, means including said relay for connecting said source across said electrodes, means connected between said grid and said one electrode for normally causing the relative potential of said grid with respect to said one electrode to have a value which renders said tube non-conducting, means located partly on the train and partly in the trackway for at times changing the relative potential of said grid with respect to said one electrode to a value which renders said tube conducting, and governing means on the train controlled by said relay.

14. In combination, a train-carried tube comprising two spaced electrodes and a grid in a medium which forms a conducting path between said electrodes when and only when the potential between the electrodes exceeds a value which depends upon the relative potential of said grid with respect to one of said electrodes, a source of electromotive force on the train, a relay, means including said relay for connecting said source across said electrodes, means located partly in the trackway for controlling the relative potential of said grid with respect to said one electrode, and governing means controlled by said relay.

15. In combination, a train-carried tube comprising two spaced electrodes and a grid in a medium which forms a conducting path between the electrodes when and only when the negative potential of the grid with respect to one such electrode is below a predetermined value, a source of electromotive force on the train, a relay, means including said relay for connecting said electrodes across said source, means located partly in the trackway for controlling the negative potential of said grid with respect to one such electrode, and governing means controlled by said relay.

In testimony whereof I affix my signature.
